(57) CLAIM

The ornamental design for a Christmas decoration, as shown and described.

DESCRIPTION

FIG. 1 is a top, perspective view of a Christmas decoration showing our new design;

FIG. 2 is a bottom, perspective view thereof;

FIG. 3 is a front view thereof;

FIG. 4 is a right side view thereof;

FIG. 5 is a left side view thereof;

FIG. 6 is a bottom view thereof; and,

FIG. 7 is a top view thereof.

The broken line showing of illumination from a circular light on the Christmas decoration is included for the purpose of illustrating only and forms no part of the claimed design.
